United States Patent Office

Des. 228,252
Patented Aug. 28, 1973

228,252

PACKAGE DISPENSER OR THE LIKE

Anthony J. De Bernardi, 34—41 85th St.,
Jackson Heights, N.Y. 11372

Filed May 25, 1972, Ser. No. 257,063

Term of patent 14 years

Int. Cl. 20—01

U.S. Cl. D52—2 R

FIG. 1 is a front elevational view of a package dispenser or the like showing my new design;

FIG. 2 is a right side elevational view thereof, the left side being a mirror image thereof;

FIG. 3 is a rear elevational view thereof; and

FIG. 4 is a top plan view thereof.

I claim:

The ornamental design for a package dispenser or the like, as shown and described.
